UNITED STATES PATENT OFFICE.

FRED K. CUDDY, OF KANSAS CITY, MISSOURI.

WORK GARMENT.

Application filed November 2, 1925. Serial No. 66,359.

My invention relates to work garments and has for its principal object to provide a combination overall consisting of separate jacket and trousers members, semi-permanently connected so that the garment may be put on or removed as a unit, but which can be separated for renewal or separate laundering of either member.

The renewal feature is an important one for the reason that the trousers wear and become soiled more quickly than the jacket, and by having the jacket and trousers members separable the expense of renewal or laundering of a complete garment may be obviated.

In accomplishing the object of my invention I provide improved details of structure, the preferred forms of which are illustrated in the accompanying drawings wherein:

Fig. 1 is a view of a combination garment embodying my improvements, illustrating its application to a wearer, flaps of the garment being turned back to illustrate the connection between the separate members.

Fig. 2 is a detail perspective view of the lower portion of the jacket, particularly illustrating the waist band construction.

Fig. 3 is a front perspective view of the waist portion of the trousers member.

Fig. 4 is a rear view of portions of the jacket and trousers, particularly illustrating the drop seat of the trousers.

Referring more in detail to the drawings:

1 designates the jacket and 2 the trousers of a combination garment embodying my improvements. The jacket 1 has a front opening 3 with the usual buttons 4 along one edge and concealed buttonholes 5 along the other edge, the body of the jacket continuing into a waist band portion 6, the corners of which are cut back to form the notches 7 for facilitating access to the upper portion of the trousers fly when the jacket is assembled with the trousers and the combined garment is in use.

45 Stitched or otherwise secured to the waist band portion at intervals thereabout are tabs 8, having buttonholes 9 for receiving buttons 10 on the waist band of the trousers section, the two rear tabs being arranged at an inward angle so that when connected with the trousers, pull on the tabs will tend to spread the trousers member and fit the same snugly at the seat. The tabs 8 are covered by a flap 11 stitched to the waist band 6 continuously about the jacket and over the edges thereof to form a downwardly opening pock-

et containing the tabs, so that the latter are protected and the waist band of the trousers concealed when the garment is assembled to provide a dust-proof garment.

60 The trousers 2 are of the conventional construction for garments of this kind, except for the side openings 12, which extend downwardly from the waist band a sufficient distance to form a drop seat 13, the edges of the drop seat and the leg portions having buttons and buttonholes 14—15 for connecting the seat to the body of the trousers.

65 The buttons 10 on the trousers waist band 16 are inside of the waist band in front and on the outside of the band at the rear of the trousers, the buttons at the back being spaced to co-operate with the inclined tabs on the jacket to draw the seat laterally as before mentioned.

70 In using the garment the jacket and trousers members may be connected either before or after the garment is put on; in either event the jacket extends into the trousers part and the flap 11 on the outside thereof so that the trousers waist band is nested 75 within the pocket formed by the jacket and its flap, the upper edges of the trousers fly being located within the ends of the pocket, one of the tabs 8 being located near each end 80 of the pocket to hold the corners of the fly therein.

85 It is apparent that a garment of this construction may be used as any ordinary one-piece overall, the flap 11 of the jacket giving the garment the one-piece appearance and protecting the connecting members.

90 Should the trousers become worn, they may be disconnected from the jacket and replaced with a new pair, or if they become 95 soiled and it is desired to wash them individually of the jacket, they may be removed and cleansed and then re-attached to the jacket.

100 What I claim and desire to secure by Letters Patent is:

1. A combination overall, comprising separate jacket and trousers members, the jacket having a waist band portion, tabs on the waist band portion, a flap extending substantially from one vertical edge of said jacket member to the other vertical edge thereof and attached to the waist band portion along its upper edge and to the front vertical edges of the jacket at its ends, forming a closed-in pocket for the tabs, the trousers having buttons for the tabs to connect the 105 110

2
two garment members, the front ends of the waist band portion being notched to expose the trousers fly.

2. A combination overall, comprising separate jacket and trouser members, the jacket member having a waist-band portion, tabs on the waist-band portion, a flap extending from one vertical edge of said jacket member to the other vertical edge thereof and attached to the waist-band portion along the upper edge of said flap and to the front vertical edges of the jacket at its ends, forming a closed ended pocket for the tabs, the trousers having buttons for the tabs to connect the two garment members.

3. A combination overall, comprising separate jacket and trouser members, the jacket

member having a waist-band portion, tabs on the waist-band portion, a flap extending from one vertical edge of said jacket member to the other vertical edge thereof and attached to the waist-band portion along the upper edge of said flap and to the front vertical edges of the jacket at its ends, forming a closed ended pocket for the tabs, the trousers having buttons for the tabs to connect the two garment members, said flap portion being of substantially the same width as said waist-band portion to have the appearance of a belt.

In testimony whereof I affix my signature.

FRED K. CUDDY.
